COMBINATION MICROPHONE AND CONTROL
STAND FOR A LOUDSPEAKING TELEPHONE
SET

Donald Michael Genaro, Haworth, N.J., and George
Willis Reichard, Jr., Indianapolis, Ind., assignors to
Bell Telephone Laboratories, Incorporated, Murray
Hill, N.J.

Filed Oct. 5, 1971, Ser. No. 186,829

Term of patent 14 years

Int. Cl. D14—03

U.S. Cl. D26—14 A

FIG. 1

FIG. 2

FIG. 3

FIG. 4

FIG. 5

FIG. 1 is a front perspective view of a combination microphone and control stand for a loudspeaking telephone set showing our new design;

FIG. 2 is a side view of the set shown in FIG. 1;

FIG. 3 is a front view of the set shown in FIG. 1;

FIG. 4 is a plan view of the base portion of the set shown in FIG. 1; and

FIG. 5 is a variant of the base portion shown in FIG. 4.

We claim:

The ornamental design for a combination microphone and control stand for a loudspeaking telephone set, substantially as shown and described.
